[57] CLAIM

The ornamental design for a reconfigurable toy lock, as shown and described.

DESCRIPTION

FIG. 1 is a front perspective view of a reconfigurable toy lock showing my new design;

FIG. 2 is a front elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a left side elevational view thereof;
FIG. 8 is a front perspective view of the design shown in FIGS. 1 through 7 in a humanoid robot configuration;

FIG. 9 is a front elevational view thereof;

FIG. 10 is a right side elevational view thereof;

FIG. 11 is a top plan view thereof;

FIG. 12 is a bottom plan view thereof;

FIG. 13 is a rear elevational view thereof; and,

FIG. 14 is a left side elevational view thereof.
